TYPEWRITER CARRIAGE RETURN DEVICE

Culbert Bowen, Salt Lake City, Utah

Application May 29, 1941, Serial No. 395,841

10 Claims.

(Cl. 197—65)

This invention relates to a typewriter carriage return device, its principal objects being to provide:

First: A mechanism that is simple, durable, and not liable to get out of order.

Second: A device that can be actuated by an operator without taking the hands away from the keyboard.

Third: A device which enables a skilled operator to keep the hands poised at all times to strike the keys in the touch system of operation, thereby relieving the operator of considerable nervous stress.

Fourth: A device that may be built permanently into a machine or that may advantageously be attached to, or detached from, a machine, at the option of an operator.

Fifth: A device that does not obstruct or encumber the usual manner of operating a typewriter.

Trained typists using the touch system of operation frequently find it very disconcerting to shift the carriage by means of the line-space lever in the ordinary way, since it makes necessary the re-poising of the hands each time a new line is begun.

By means of the invention, an operator is enabled to accomplish the return shift of the carriage independently of hand motion, using for example, a foot to accomplish this task, thereby not distracting the attention in order to perform a merely perfunctory movement.

In the accompanying drawing, which illustrates one embodiment of the invention:

Fig. 1 represents in plan, a general outline of an ordinary typewriting machine, the same being equipped with the device of the invention;

Fig. 2, a front elevation, and

Fig. 3, a side elevation.

Referring to the drawing, the numeral 10 designates a typewriting machine of well known construction provided with the usual carriage 12 on which is mounted the usual platen 14 and the usual carriage-return line-space lever, or briefly, the line-space lever 15. The carriage as usual, may be returned towards the right to a position indicated for example, at 12—1, this position determining the beginning of the line as usual.

What is novel will now be described.

Mounted on the frame structure of the typewriter machine is a conduit 16 which may advantageously consist of a tube made of metal or other suitable material. The conduit may be provided with goosenecks 17 and 18, the former being fastened to the upper part of the machine 55

frame in front of and just below the platen 14, while the latter may be fastened to the lower part, in this instance, at the right of the machine structure. The fastenings between the 5 goosenecks and the frame structure may be semi-permanent, consisting for example, of a screw or small bolt, not shown, while on the other hand, the goosenecks may be detachably connected to the frame by means of removable clamps indicated at 19.

Engaging the line-space lever, for example, by means of a ring 20 slipped over the upturned thumb portion 15—2, is a flexible connector 21 which passes through an entry 24 leading into the conduit 16, and the connector, after passing through the curved portion of the conduit, may advantageously emerge through an exit 25 and extend downwardly to any suitable actuating element for imparting return propelling energy to the flexible connector. It should be noted that the curved portion of the conduit, which is disposed intermediate the length of the conduit, is preferably curved along an arc having a comparatively long radius.

Since an important object of the invention is to allow an operator to concentrate his attention upon the keyboard of the machine and to keep the hands constantly poised in the proper position for operating the type keys, it is convenient 30 to operate the carriage-return mechanism by means of foot power. For this purpose, a treadle 26 may advantageously be provided. In the present instance, the treadle is pivoted at 27 and has the short lever arm 28 which terminates in a combined counterweight and stop 29. A heel-piece 30 enables the operator to comfortably rest a foot 31 on the treadle. Normally, the treadle is in the position 26 indicated in the drawing, but when the carriage is to be returned to the 40 beginning of a line, the operator presses the foot 31 forward, causing the long arm of the treadle to descend to a position indicated for example, by the dotted lines at 26—1.

The treadle pivot 27 may be mounted in a stationary stand 32, the stand being either fastened to the floor by any suitable means (not shown), or it may, as contemplated in the present instance, be made of sufficient weight as to be not likely to displacement under ordinary circumstances of use.

It is an object of the invention to arrange the foot-power unit so as to be largely non-fatiguing to the operator. This is accomplished by arranging the two arms of the treadle somewhat after the proportions indicated in Fig. 3, where

the back of the operator's foot is naturally caused to remain by gravity approximately in the position shown, and where the stop 29 provides a positive support for the heel, the pivot 27 being located almost directly under the instep of the foot. The lower extremity of the flexible connector 21 may be connected to the long arm of the treadle 26, as indicated in Fig. 3.

For convenience, the present drawing shows the machine 10 located at the end of a table 34, but it is to be understood that the device is adaptable to being located on an ordinary typewriter desk or other suitable support.

While the conduit 16 is preferably in the form of a tube, suitably plated or otherwise finished to harmonize with the finish of any particular typewriter, it might sometimes be in the form of a channel open at the top. The channel construction is not shown, since it requires only mechanical skill to make the substitution. The conduit 16 is shown in a position where it does not interfere with the convenience of operation of the machine, but it is obvious that it is not necessarily restricted to that exact position.

It may be stated that in some kinds of typewriting, especially intermittent work, the device might not be of any particular utility, and in such cases, the ring 20 can easily be unhooked from the thumb grip 15—2, and the flexible connector be pulled through the conduit until the ring 20 comes to rest at the entry 24.

The particular utility of the device is conspicuous in the writing of any lengthy documents, such as court records, specifications, and many other kinds of voluminous writing.

The device in no way obstructs the normal operations of a typewriter, leaving the keyboard 35 free and open, but the portable form of the device makes it possible to easily and quickly remove it, should occasions arise where this is desired. All that is necessary for removing the device, is to loosen the clamps 19 and lift off the ring 20.

Obviously, means other than foot-power can be used to furnish the propelling energy for returning the carriage to the beginning of a line, but in any event, as soon as the carriage is so returned, the connector 21 is slackened as indicated at 21—2 in Fig. 3. The present instance shows this to be accomplished by allowing the foot to come to its natural repose on the foot plate 38 forming a part of the treadle. Thus, the foot is relaxed during the writing intervals, and the connector is drawn taut, as at 21, only during the short intermittent periods of actually propelling the carriage on its return trips.

The precise length of the connector can be finally adjusted by moving the stand or pedestal 32 slightly back or forth as the case may require, and the pedestal may hold such position by means of friction pads 37 bearing on the floor, the pads being soft rubber or other suitable material.

It will be self-evident to a skilled person that numerous changes can be made in the specific arrangement of the mechanical organization of the invention as hereinbefore described, without avoiding the terms of the following claims.

Having fully described my invention, what I claim is:

1. In a typewriting machine having a frame; a carriage; and a platen and line-space lever mounted on the carriage; the combination of a flexible connector having one end thereof removably attached to the said line-space lever; a conduit for the flexible connector, the said conduit

extending along and in front of the said frame and terminating in a curved portion depending over the said frame at the side thereof which is opposite that from which the said line-space lever extends, the conduit further, having an entry in front of the said frame for the flexible connector and an exit leading from the curved portion, for the flexible connector; and means operative to propel the flexible connector in the direction of return of the carriage.

2. In a typewriting machine, the combination recited in claim 1, wherein the conduit extremity which extends along and is disposed in front of the typewriter frame is attached to the upper part of the typewriter frame at that side thereof from which the said line-space lever extends, and wherein the other conduit extremity is attached to the lower part of the typewriter frame at the opposite side thereof.

3. A carriage-return device for a typewriting machine or the like having a carriage normally operable to move across the machine substantially horizontally from one side to the other side thereof, and adapted for quick return to the said one side, the said carriage having attaching means secured thereto near that end thereof which corresponds to the said other side of the machine, said carriage-return device comprising a conduit curved intermediate its length and having a substantially straight end portion; means for maintaining said conduit in a fixed position relative to said carriage and to said machine with its said straight end portion disposed substantially horizontally in front of the path of travel of said carriage and extending along a part of the width of said machine at the said one side thereof, and with its opposite end portion extending downwardly along the said one side of the machine; a flexible connector passing through said conduit and having its upper end adapted for attachment to the said attaching means of said carriage; and means attached to said flexible connector adjacent the lower end thereof for enabling said flexible connector to be pulled quickly.

4. A carriage-return device according to claim 3 wherein the curved intermediate portion of the conduit is curved along an arc having a comparatively long radius.

5. A carriage-return device for a typewriting machine or the like according to claim 3 wherein said means for maintaining said conduit in a fixed position comprises a leg adapted to be attached to the upper part of the said other side of said machine and a leg adapted to be attached to the lower part of the said one side of said machine.

6. A carriage-return device for a typewriting machine or the like having a carriage normally operable to move across the machine substantially horizontally from one side to the other side thereof, and adapted for quick return to the said one side, the said carriage having attaching means secured thereto near that end thereof which corresponds to the said other side of the machine, said carriage-return device comprising a tube, curved intermediate its length and having a substantially straight portion adjacent one end of the curved portion, the ends of said tube being adapted for securement to opposite sides of the machine, one adjacent the top and the other adjacent the bottom of the machine, and said tube being formed such that, when attached to the machine, the said straight portion thereof occupies a fixed, substantially horizontal posi-

tion in front of the path of travel of the carriage and along the width of the machine, and an opposite portion extends downwardly along the said one side of the machine with the said curved portion occupying a fixed position adjacent the said one side of the machine, said tube having an opening formed intermediate the ends of the said straight portion thereof and an opening formed adjacent that end of the said intermediate curved portion thereof which lies within that said portion thereof which is adapted to extend downwardly, whereby a conduit is formed through that portion of said tube which is adapted to be disposed adjacent said one side of the machine; a flexible connector passing through said conduit and having its upper end adapted for attachment to the said attaching means of said carriage; and means attached to said flexible connector adjacent the lower end thereof for enabling said flexible connector to be pulled quickly.

7. A carriage-return device according to claim 6 wherein the curved intermediate portion of the conduit is curved along an arc having a comparatively long radius.

8. In a typewriting machine having a frame, and a platen-carrying carriage mounted in said frame near the top thereof for substantially horizontal sliding movement across said frame from one side to the other side thereof during normal operation of said machine, and for quick return

5 to the said one side; the combination of a conduit, curved intermediate its length and having a substantially straight end portion; means maintaining said conduit in a fixed position relative to said carriage with its said straight end portion disposed substantially horizontally in front of the path of travel of said carriage and extending along a part of the width of said machine at the said one side thereof, and with its opposite end portion extending downwardly along the said one side of the machine; attaching means secured to that end of said carriage which corresponds to the said other side of the machine; a flexible connector passing through said conduit and having its upper end attached to the said attaching means of said carriage; and means attached to said flexible connector adjacent the lower end thereof for enabling said flexible connector to be pulled quickly.

10 9. In a typewriting machine, the combination recited in claim 8 wherein the curved intermediate portion of the conduit is curved along an arc having a comparatively long radius.

15 10. In a typewriting machine, the combination recited in claim 8 wherein said means for maintaining said conduit in a fixed position comprises a leg attached to the upper part of the said other side of said machine and a leg attached to the lower part of the said one side of said machine.

CULBERT BOWEN.
